INVENTOR

George A. Louque.

BY
James D. Shatto & Co,

ATTORNEYS.

UNITED STATES PATENT OFFICE.

GEORGE A. LOUQUE, OF NEW ORLEANS, LOUISIANA, ASSIGNOR TO CARMELITE LOUQUE, OF NEW ORLEANS, LOUISIANA.

ARTIFICIAL TOOTH.

1,351,578.

Specification of Letters Patent. Patented Aug. 31, 1920.

Application filed March 2, 1920. Serial No. 362,648.

To all whom it may concern:

Be it known that I, GEORGE A. LOUQUE, a citizen of the United States, residing at New Orleans, in the parish of Orleans and 5 State of Louisiana, have invented new and useful Improvements in Artificial Teeth, of which the following is a specification.

My present invention pertains to dentistry and it contemplates the provision of 10 artificial teeth that are strong and durable and when properly positioned in the gums of a patient will present a finished and natural appearance.

The invention also contemplates the provision of artificial teeth that are quickly and 15 easily applied and capable of use in dental crowns as well as in bridge work.

The invention in all of its details will be 20 fully understood from the following description and claims when the same are read in connection with the drawings, accompanying and forming part of this specification, in which:

Figure 1 is a side elevation of a bicuspid 25 tooth.

Fig. 2 is a detailed view of the metal support that fits into the slots of the bicuspid teeth.

Fig. 3 is a front elevation of the support 30 as applied to said tooth.

Fig. 4 is a side elevation showing in dotted lines how the support rests below the upper end of the tooth.

Fig. 5 is a longitudinal section of Fig. 10, 35 and, Fig. 6 is a transverse section of Fig. 9.

Similar numerals of reference designate corresponding parts in all of the views of the drawings.

As clearly shown in Fig. 1 the molar and 40 bicuspid tooth 7 is provided with a slot 8 that extends slightly below the longitudinal center of the tooth and on each side of said slot 8 and on the front and rear surfaces of said tooth I provide channels or grooves 45 9. The grooves 9 extend to a point slightly below the lower end of the tooth as illustrated.

The metal support (Fig. 2) is provided 50 with the portions 10 that straddle the outer sides of the tooth 7 and said portions 10 are secured to each other by the portion 11, (Fig. 5). This portion 11 is of a corresponding length to that of the slot 8 of tooth 7. The portions 10 are provided on the in-

ner edges with tongues 12 and said tongues 55 extend the full height of the portions 10.

It will be seen, by reference to Fig. 4 that the tooth 7 extends at its rear and front sides slightly above the metal support and hence the tooth may readily and easily straddle the gums of the patient.

It will be further gathered from the foregoing that when it is desired to assemble the device shown in Figs. 1 to 6 inclusive, it is simply necessary to push the support into 65 the slot 8 and channels 9 and then the tooth may be rigidly secured to said support by the use of cement.

The construction illustrated is simple and 70 inexpensive and through its use the appearance and beauty of the patient's mouth will be greatly enhanced and yet cleanliness of the mouth and teeth is at all times assured.

I would distinctly have it understood that 75 the device illustrated may be used either in artificial teeth or in bridge and crown work. Moreover, I do not wish to limit myself to the exact material of which the teeth and support are formed for the reason that in the future use of the invention such changes 80 or modifications may be made as fairly fall within the scope of my claims appended.

It will also be apparent that the device as 85 a whole is strong and will remain rigid in the gums of the patient.

Having described my invention, what I claim and desire to secure by Letters-Patent is:—

1. In an artificial tooth the combination 90 of a body portion, a longitudinal central groove extending from the upper end of said body to a point slightly beyond the transverse center thereof, channels formed on the front and rear face of the body and on each side of the groove, and a support having a 95 portion that seats in the groove, and further having portions that are connected together by the first named portion; said last named portions being so constructed and arranged that they rest in the channels of the body portion.

2. In an artificial tooth, the combination 100 of a body portion, a slot formed in the center thereof with respect to its width, channels formed on each side of the slot and 105 on the front and rear surfaces of the body portion, and a support that straddles the body portion and comprising a front and

rear portion, a portion that retains the front and rear portions with respect to each other and constructed and arranged to snugly occupy the slot of the body portion and 5 tongues formed on the inner edges of the front and rear portions that rest in the channels of the body portion.

3. An artificial tooth comprising a body member, a slot formed in said body member, 10 channels adjacent the slot and a support having a portion that rests in the slot and

also having tongues that rest in the channels of the body member; said member having a depression in its upper end in which the upper end of the support rests.

15

In testimony whereof I have hereunto set my hand in presence of two subscribing witnesses.

GEORGE A. LOUQUE.

Witnesses:

J. PONIS,
F. E. ASHMOORE.
